UNITED STATES PATENT OFFICE

JAMES L. BALTON, OF BALTIMORE, MARYLAND

DESIGN FOR AN ICE-CREAM CONE

Application filed February 28, 1929. Serial No. 30,253. Term of patent 14 years.

To all whom it may concern:

Be it known that I, JAMES L. BALTON, a citizen of the United States of America, residing at city of Baltimore and State of Maryland, have invented a new, original, and ornamental Design for Ice-Cream Cones, of which the following is a specification, reference being had to the accompanying drawing, forming part thereof.

In the drawing,

The figure is an elevational view of an ice cream cone, showing my new design.

I claim:

The ornamental design for an ice cream cone, as shown.

JAMES L. BALTON.
